DOUBLE ACTING TWO-STROKE INTERNAL COMBUSTION ENGINE

Filed Sept. 19, 1929

UNITED STATES PATENT OFFICE

MAX TRECHSEL, OF WINTERTHUR, SWITZERLAND, ASSIGNOR TO THE FIRM OF SULZER
FRÈRES SOCIETE ANONYME, OF WINTERTHUR, SWITZERLAND

DOUBLE-ACTING TWO-STROKE INTERNAL COMBUSTION ENGINE

Application filed September 19, 1929, Serial No. 393,688, and in Switzerland October 30, 1928.

This invention relates to double-acting two-stroke internal combustion engines and in particular to engines in which both the cylinder body and its liner are transversely divided and furnished with an intermediate connecting member.

In known double-acting two-stroke internal combustion engines constructed in this manner the working forces occurring in the axial direction are transmitted to the cylinder cover through the parts of the cylinder liner, whereby undue stresses are imposed on the engine, and particularly on the parts of the cylinder liner, which often give rise to disturbances in working. Further in engines of this type difficulties arise in cleaning and repairing owing to the necessity for undoing pipe connections in order to withdraw the parts of the divided cylinder body from one another.

The object of the present invention is to obviate these disadvantages, and to this end the arrangement is such that the axial working forces set up in each half cylinder taken as a whole are transmitted through the cylinder body to the intermediate member or to the frame, the two halves of the cylinder liner abutting against one another for centering purposes with axial play but without packing in the neighborhood of the ports, whereby the half cylinders are left free of air inlet or exhaust pipe connections.

A convenient construction of vertical double-acting internal combustion engines according to the invention is illustrated by way of example in the accompanying drawing, in which

Figure 1 is a longitudinal section through the cylinder.

Fig. 2 shows the upper half of the cylinder of a machine in accordance with Fig. 1, when removed.

Fig. 3 shows the lower half of the cylinder of an internal combustion engine, in accordance with Fig. 1, and in the broken line, the piston in its extreme (highest) position.

Fig. 4 shows the bayonet cap from above.

In the construction illustrated, the piston 1 mounted on the piston rod 2 is disposed in a cylinder comprising a lower cylinder

head 3, an upper cylinder head 4, and a liner divided into upper and lower halves 5 and 6. The upper cylinder body 7 and the lower cylinder body 8 are held together by means of the intermediate member 9 and bolts 24. 55 Bolts 23 pass through the upper cylinder body 7 and enter the cylinder liner 5 and secure the cylinder liner to the cylinder body.

In a cover 20 in the upper cylinder head is inserted a valve casing 10, containing for example the injection and starting valves. The injection valves for the lower half of the cylinder are omitted for simplicity. The lower cylinder head is provided with a stuffing box 11 for the piston. Cooling water 65 chambers are provided at 21 in the cover, at 12 in the upper cylinder half and at 13 in the lower cylinder half. Scavenging air enters through the ports 14, and charging air through the ports 15, whilst the exhaust gases 70 are led away through the ports 16. The upper liner, and therefore also the upper cylinder half, is centred by means of the circular guide 17 on the lower liner.

The scavenging and charging are effected 75 in the well-known manner. At the end of the expansion stroke the piston first uncovers the charging air ports 15, the exhaust gases being prevented from escaping into the charging air vessel by means of valves (not shown). 80 After uncovering the ports 15, the piston opens the exhaust ports 16 to equalize the pressure in the working cylinder and then the scavenging air ports 14 whereupon the scavenging air enters the cylinder and drives 85 the exhaust gases in the cylinder out through the exhaust ports.

On its return stroke the piston first closes the scavenging ports 14 and then the exhaust ports 16. Since the charging air pressure is 90 greater than that in the cylinder, the charging air inlet valves open and additional air enters the working space until the piston closes the ports 15, whereupon air compression and fuel injection and ignition take place 95 in the well-known manner followed by the expansion of the working gases.

An important feature of this arrangement is that the joint between the upper and lower cylinder halves (see Figures 2 and 3) is such 100

that the packing joints for the water chambers 12 and 13 (with the exception of the pipe connection for the cooling water inlet and outlet) as well as the scavenging and exhaust pipe connections do not have to be detached when the upper cylinder half is removed. The two cylinder halves are centred by means of the liners, thus giving greater accuracy in centering than could be obtained by means of the cylinder bodies or like parts of large diameter whose manufacture and expansion during running might give rise to centering errors.

The portion of the lower cylinder half containing the connections for the scavenging air and exhaust pipes is flared at the top in such a way that when the upper cylinder half is removed there is sufficient space between the piston, when in its uppermost position, and the middle portion carrying the connections for the scavenging air and exhaust ports for the piston to be inspected right down to the bottom. By the aid of mirrors even the under surface of the piston and the piston rod can be seen. In this position the piston can be completely cleaned and all the piston rings can be replaced. It should be noted that this is possible without disturbing the crosshead or the connecting rod. When replacing the upper half of the cylinder one joint only has to be remade, namely between the upper cylinder body 7 and the middle member 9 at the joint 18. This joint is readily accessible from outside and has only to withstand pressures not exceeding the scavenging air pressure, i. e. excess pressures of at most some 0.2 to 0.3 atmospheres.

If the lower liner needs renewing, it can be at once withdrawn, after removal of the upper cylinder half and the piston, as soon as the bayonet joint 19 of the lower cylinder cover has been unfastened. This is accomplished, referring to Fig. 4, by rotating the ring 19 in a manner such that the upper screw 30 which is on the axis B when the bayonet lock is closed, enters the axis A; after which operation the ring 19 can be directly removed in a downward direction. In Fig. 4 the circles 30 indicate screws. The latter appear as circles, because the six-edge screw head is on the reverse of the ring 19. The ring 19 is a portion of the bayonet lock as can be seen in Fig. 4; the other portion is on the lower cylinder head 22. In this case also in contradistinction to the known constructions the connections for the scavenging air and exhaust pipes do not have to be broken and the lower cylinder half and the intermediate member do not need to be moved.

The lower cover 22 carrying the stuffing box may be withdrawn upwardly either alone or together with the lower liner. The lower, as well as the upper cylinder cover are

so constructed that they transfer the working forces acting on them directly to the cylinder body without the aid of tension bolts. In this way the forces acting on the cylinder covers are taken up with a high degree of safety, and moreover the dimensions of the connecting bolts 23 can be reduced.

With the arrangement described the height required for dismantling the piston and piston rod is considerably less than that necessary with previously known constructions. In order to effect this dismantling laterally the lower end of the piston rod need not be raised above the cover bolts, but only above the centre member. The height of the building necessary to house the engine may therefore be reduced to the greatest possible extent. The whole arrangement permits the time and work required for the regular examination and overhaul of the engine to be considerably reduced.

The intermediate member 9 may, if desired, be cast in one piece with the lower cylinder body instead of being separate therefrom as shown.

The invention may also be used with horizontal engines, in which case the arrangement above described is applicable, reference to the "lower" cylinder half being taken to apply to the cylinder half "nearer the crank" and those to the "upper" cylinder half to apply to the cylinder half "remote from the crank."

I claim:

1. In a double-acting two-stroke internal combustion engine, a transversely divided cylinder body, abutting cylinder liners disposed in axial alignment having scavenging air ports, charging air ports and exhaust air ports adjacent the line of abutment of the liners, and an intermediate connecting member disposed between said divided cylinder body, said intermediate member having passages therein connecting with the scavenging air ports, the charging air ports, and the exhaust air ports.

2. An apparatus according to claim 1, wherein the portions of the cylinder liner and the cylinder body on the same side of the line of division are secured together.

3. An apparatus according to claim 1, including scavenging air, charging air and exhaust conduits connected to the intermediate connecting member.

In testimony whereof I have affixed my signature.

MAX TRECHSEL.
